(57) **CLAIM**

The ornamental design for a mattress border, as shown and described.

DESCRIPTION

FIG. 1 is a right top perspective view of a mattress border showing the invention;

FIG. 2 is a right side elevational view of the mattress border of FIG. 1, wherein the left side elevational view is a mirror image thereof;

FIG. 3 is a left bottom perspective view of the mattress border of FIG. 1; and,

FIG. 4 is a front elevational view of the mattress border of FIG. 1, wherein the rear elevational view is identical thereto.
